Absorbent Article sold by The Procter & Gamble Co. (Photocopy Exhibits A and B) date unknown.

Primary Examiner—Stella Reid
Attorney, Agent, or Firm—Matthew P. Fitzpatrick; Jeffrey V. Bamber

[57] **CLAIM**

The ornamental design for a surface pattern for disposable absorbent article, as shown and described.

DESCRIPTION

The FIGURE is a top plan view of a surface pattern for a disposable absorbent article, showing our new design.

The broken line showing of the disposable absorbent article is for illustrative purposes only and forms no part of the claimed design.
